UNITED STATES PATENT OFFICE.

GEORGE P. TAYLOR, OF CLINTON, MASSACHUSETTS.

SHEARS.

No. 851,708.

Specification of Letters Patent.

Patented April 30, 1907.

Application filed September 25, 1905. Serial No. 280,097.

To all whom it may concern:

Be it known that I, GEORGE P. TAYLOR, a citizen of the United States, residing at Clinton, in the county of Worcester and State of Massachusetts, have invented a new and useful Shears, of which the following is a specification.

This invention relates to a pair of shears especially designed for use in trimming lawns.

10 The especial object of this invention is to provide a light, durable, efficient and inexpensive pair of shears which can be used in trimming a lawn by a person standing in upright position.

15 A further object of this invention is to construct the parts of sheet metal so that the same can be stamped out in quantities at comparatively low cost.

To these ends, this invention consists of 20 the shears and of the combinations of parts therein as hereinafter described and more particularly pointed out in the claims at the end of this specification.

In the accompanying two sheets of drawings, Figure 1 is a perspective view of a pair 25 of shears constructed according to this invention. Fig. 2 is a fragmentary view of the operating piece of the movable handle. Fig. 3 is a perspective view of the movable shear-blade. Fig. 4 is a fragmentary perspective 30 bottom view of the construction. Fig. 5 is a perspective view of the cover-plate for housing the working parts. Fig. 6 is a sectional view taken on the line 6—6 of Fig. 1. Fig. 7 is a perspective view of a modified construction 35 with the cover-plate omitted. Fig. 8 is a fragmentary view of the operating plate of the movable handle. Fig. 9 is a detail view of the catch for holding the movable blade 40 open until released by closing of the shear-handles. Fig. 10 is a perspective view of the gear segment for operating the movable shear-blade. Fig. 11 is a detail view of the closing 45 spring, and Fig. 12 is a sectional view of the construction illustrated in Fig. 7.

In a pair of shears constructed according to this invention, the shears are operated by handles of sufficient length to permit a person to use the same for cutting grass while standing in an upright position, the cutting blades of the shears being located at an angle with respect to the handles.

Referring to the accompanying drawings for a detail description of a pair of shears constructed according to this invention, Fig. 1 shows the simpler form of shears embody-

ing this invention, in which the movable cutting blade is operated by a geared connection from a movable handle; while the second sheet of drawings illustrates a construction in 60 which the movable blade is operated in such a way that the cutting blades will snap together with spring pressure.

Referring to the first sheet of drawings, the pair of shears illustrated thereby comprises a 65 sheet metal angle-piece having the horizontal part 15 and the upwardly extending inclined part 16. Formed with and extending from the horizontal part 15 is a fixed shear blade 17, and extending from the inclined part 16 70 is the handle-tang or piece 19. The fixed shear-blade is preferably provided with a serrated or saw-toothed cutting edge 18, and the entire sheet metal stamping is preferably strengthened by corrugations 20 and 21, the 75 corrugation 21 extending part-way into the handle-tang 19 and also along the length of the fixed shear blade 17. The movable shear blade 22 is provided at one side of its pivot with a strengthening corrugation 23, and at 80 its other side has gear-teeth to be operated from the movable handle as hereafter referred to. The pivotal connection between the shear blades 17 and 22 is secured by a bolt 24 and nut 26 which clamps the blades 85 together by means of a spring washer 14. The spring-washer 14, as shown in Fig. 4, is cut out to fit over the strengthening corrugation 21 and is also notched to have the requisite spring action for holding the shear blades 90 together with the spring tension required for producing the best cutting action. The movable shear blade is operated by a handle-piece 27 which is pivoted on a screw 28 on the inclined part of the angle piece. At its 95 lower end the movable handle piece 27 has gear-teeth meshing with the gear-teeth of the movable blade, and above its pivot the handle-piece 27 is provided with a handle-tang 100 for fitting into the movable handle 31. The 100 movable parts are preferably protected by an angle cover-plate 32 which may be stamped out with strengthening corrugations 33. The cover-plate 32 is fastened in place by a screw 36 which passes through a slot 37 in 105 the movable handle-piece 27, and by a screw 34 which passes through a slot 35 in the movable shear-blade. In this construction it will be seen that the geared connection reverses the relative motion between the operating piece and cutting blade, so that when the handles are brought together the shear-

blades will close. In the use of this form of shears also the weight is carried substantially by the fixed handle, and as the entire construction is comparatively light, the shears 5 may be operated with very little labor to trim the edges of lawns or grass-plots in a direct and efficient manner.

In some cases, instead of gearing the movable shear-blade to the handle so as to secure 10 a direct cutting action, it is desirable that the movable shear-blade should be operated by a click or pawl motion so that the cutting action will be produced by spring pressure. A construction for doing this is shown in the 15 second sheet of drawings. As illustrated in Fig. 7, an angle-piece or support is provided with a horizontal part 40 and an upwardly extending angle part 41. Carried by the horizontal part 40 is the fixed shear-blade 42 having a strengthening groove or corrugation 43 and preferably a serrated or saw-toothed cutting edge. Extending up from the inclined part 41 is a handle-tang 44 for receiving the fixed handle 60. The movable 20 cutting blade 45 is pivoted on a screw 46 threaded into the horizontal part of the angle-piece. The parts as thus far referred to are of substantially the same construction as the corresponding parts of the form of shears 25 illustrated in the first sheet of drawings. In order to operate the movable shear-blade by spring pressure, the movable shear-blade is provided with a pin 47 and the fixed shear-blade with a pin 48 extending up through a 30 slot in the movable shear-blade. Engaging the pins 47 and 48 is a strong bent spring 49 which will normally hold the shear-blades closed. In order to operate the movable shear-blade so that the same will be released 35 and allowed to close under spring pressure, the movable shear-blade is provided at its rear edge with gear-teeth. Meshing with the gear-teeth of the movable shear-blade 45 are gear-teeth of an operating sector 50. The sector 50, as shown in Fig. 10, is provided at one edge with a turned down flange 51. The sector 50 is pivoted on a pivot-screw at a perforation 53, and also pivoted on the screw is a handle-piece 54 which is connected to the movable handle 61. Co-operating with the sector 50 is a spring-plate having a catch 52 for holding the shears open until the handles are nearly closed. The handle-piece 54, as shown in Fig. 8, is provided on its under side with a lug 55 which will force down the spring-plate 52 to release the cutting blade when the handles are closed together. In the use of a pair of shears as thus constructed, the handle-piece of the movable 55 handle will turn the operating sector to open the cutting shears when the handles are spread apart until the parts reach the position shown in Fig. 7, when it will be seen that the catch 52 will lock the operating sector 60 against return motion. When the movable

handle is being swung back to closed position, the shears will remain open until the spring-plate is forced down by the lug 55 of the handle-piece 54. When this takes place, the cutting jaw will be released and will snap 70 to closed position under the force of its spring. In this construction, also, it will be seen that the parts are preferably pressed out of sheet metal forming very light and strong shears which will have the advantage of quick clos- 75 ing action.

I am aware that many changes may be made in the proportions and shapes of parts by those who are skilled in the art without departing from the scope of my invention as 80 expressed in the claims. I do not wish, therefore, to be limited to the particular forms of shears which I have herein shown and described, but

What I do claim and desire to secure by 85 Letters-Patent of the United States is:—

1. As an article of manufacture, a pair of shears comprising an angle-piece having a horizontal part with fixed cutting blade, a rearwardly inclining part with fixed handle, 90 a movable cutting jaw pivoted on the horizontal part of the angle piece, a movable handle pivoted on the inclined part of the angle-piece and means connected with the handle for operating said movable jaw. 95

2. As an article of manufacture, a pair of shears comprising an angle-piece having a horizontal part with fixed horizontal cutting blade, a rearwardly inclined part with fixed handle, a movable horizontal cutting jaw piv- 100 oted on the horizontal part of the angle-piece, and a movable handle pivoted on the inclined part of the angle-piece, said movable cutting jaw and movable handle having a reverse motion connection causing the cutting jaws to 105 open when the handles are separated.

3. As an article of manufacture, a pair of shears comprising an angle-piece having a horizontal part with fixed horizontal cutting blade, a rearwardly inclining part with fixed 110 handle, a movable shear-blade pivoted to the horizontal part of the angle-piece on a vertical axis and having gear-teeth, and a movable handle pivoted on the inclined part of the angle-piece with gear-teeth meshing 115 with the gear-teeth of the movable shear-blade.

4. As an article of manufacture, a pair of shears comprising an angle-piece having a horizontal part with fixed shear-blade, a 120 rearwardly inclining part with fixed handle, a movable shear-blade, a vertical pivot-bolt with spring-washer thereon for mounting the movable shear-blade on the horizontal part of the angle-piece, and a movable handle 125 pivoted on the inclined part of the angle-piece and connected to operate the movable shear-blade.

5. As an article of manufacture, a pair of shears comprising an angle-piece having a 130

horizontal part with fixed shear-blade, a rearwardly inclining part with fixed handle, a movable shear-blade pivoted on the horizontal part of the angle-piece, and an angular 5 cover-plate fastened on the angle-piece and protecting the working parts.

6. As an article of manufacture, a pair of shears comprising an angle-piece having a horizontal part with fixed shear-blade, a 10 rearwardly inclining part with fixed handle, a movable shear-blade pivoted on the horizontal part of the angle-piece with gear-teeth, a movable handle pivoted on the rearwardly inclined part of the angle-piece with 15 gear-teeth meshing with the gear-teeth of the movable blade, and a cover-plate fastened to the angle-piece and inclosing the working parts.

7. As an article of manufacture, a pair of 20 shears comprising a fixed handle and fixed shear-blade, a movable shear-blade pivotally connected with the fixed shear-blade, a spring normally closing the movable shear-blade, a catch for holding the movable shear-blade open, and a movable handle having 25 means for releasing the catch to permit the movable shear-blade to close.

8. As an article of manufacture, a pair of shears comprising an angle-piece having a 30 horizontal part with fixed shear-blade, a rearwardly inclining part with fixed handle, a movable shear-blade pivoted on the horizontal part of the angle-piece and having gear-teeth, a gear-piece pivoted on the inclined part of the angle-piece and meshing with the gear-teeth of the movable shear-blade, a spring-plate having a catch holding the movable blade open, a spring for normally closing the movable shear-blade, a 35 movable handle turning with the gear-piece to open the shears and bending the spring to release the movable shear-blade as the handles are closed.

9. As an article of manufacture, a pair of 40 shears comprising a fixed shear blade, a fixed handle connected therewith, a movable shear blade having gear teeth, a gear piece pivotally mounted with respect to the fixed shear blade and having teeth meshing with the 45 gear teeth of the movable shear blade, a spring plate having a catch for holding the

movable blade open, a spring for normally closing the movable shear blade, and a movable handle for turning with the gear piece to open the shears and bend the spring to release the movable shear blade as the handles 55 are closed.

10. As an article of manufacture, a pair of shears comprising two shear blades pivotally connected together, a handle for each shear 60 blade, an intermediate piece located between one shear blade and its handle and pivotally connected with said handle, said intermediate piece having means for operating the shear blade, a spring plate having a catch for holding the intermediate piece in such position as to hold the blades open, and means on the movable handle for disengaging the catch from the intermediate piece to allow the blades to close.

11. As an article of manufacture, a pair of shears comprising two shear blades movably connected together, a spring plate having a catch for holding the blades open, and a handle for operating one of the blades having 75 means for disengaging the catch to allow the blades to close.

12. As an article of manufacture, a pair of shears comprising an angle piece having a 80 fixed shear blade, a fixed handle connected with the angle piece, a movable shear blade pivoted on the angle piece, and a cover plate fastened on the angle piece to protect the working parts.

13. As an article of manufacture, a pair of 85 shears comprising pivoted cutting blades, pivoted handles, and a multiplying connection between one of the handles and a cutting blade, comprising a gear segment connected with the handle, and a gear segment with 90 shorter radius meshing therewith and connected with the blade for securing a different angular movement of the cutting blade from the angular movement of the handle which operates the same.

In testimony whereof I have hereunto set my hand, in the presence of two subscribing witnesses.

GEORGE P. TAYLOR.
